CENTRIFUGAL CONCRETE MOLDING
MACHINE

Henry A. Wiesner, Lemay, Mo.

Application April 8, 1947, Serial No. 740,119

9 Claims. (Cl. 25—41)

1

The principal object of this invention resides in providing an improved mold for producing concrete practice bombs or similar articles.

An important purpose of the invention consists of providing an improved means for conveniently and satisfactorily rotating a concrete mold for subjecting the concrete material therein to the effects of centrifugal force, thereby producing a better finish and a superior article.

An additional object of the invention is to provide an improved arrangement for controlling the rotation of a mold; for agitating the contents of a mold to produce more uniform filling of the mold; and for readily stopping the rotation of the mold after centrifugal force has been applied to the contents.

Another important aim of the invention consists in providing a novel and superior fastening means for centering, journaling and supporting a mold for rotation.

Still another intention of the invention is to provide a combined mold filling and centering and journaling means.

Yet another important purpose of the invention is to provide an effective means for producing pointed ends upon articles formed in said mold during rotation thereof.

And a final specific object of the invention to be enumerated herein is to provide a centrifugal type of molding apparatus wherein a mold may be more easily centered and secured to the rotatable portion of the apparatus, may be quickly and easily filled with concrete material; wherein a convenient arrangement is provided for selectively agitating the mold to pack its contents and to rotate the mold as desired for applying centrifugal force thereto; wherein an improved arrangement of brake means is provided for stopping the rotation of the mold as desired; and wherein conveniently and accessibly disposed control mechanism is provided for actuating each of the above instrumentalities.

These, together with various ancillary objects of the invention which will later become apparent as the following description proceeds, are attained by this device, a preferred embodiment of which has been illustrated, by way of example only, in the accompanying drawings, wherein;

Figure 1 is a side elevational view of a preferred embodiment of the invention, parts being broken away, and an alternative position in the operation of the device being indicated by dotted lines;

Figure 2 is a side elevational view of the device taken at right angles to the showing of Figure 1;

Figure 3 is a top plan view of the apparatus; 55

Figure 4 is a fragmentary view, taken chiefly in vertical longitudinal sections, certain parts being shown in elevation, and illustrating the construction of the rotatable base of the apparatus;

5 Figure 5 is a horizontal sectional view taken substantially upon the section line 5—5 of Figure 4 and illustrating the rotating gearing of the device;

10 Figures 6 and 7 are horizontal sectional views taken upon the section line 6—7 of Figure 4, and illustrating respectively an electro-magnetically operated and a hydraulically operated brake means for stopping the rotation of the mold;

15 Figure 8 is an elevational view, parts being broken away and shown in sections, of a mold and a portion of its supporting base, and effecting the operation of the device;

20 Figure 9 is an enlarged fragmentary view, taken in vertical transverse section through the filling neck of the mold and associated parts; and,

Figure 10 is a horizontal sectional detailed view taken substantially upon the section line 10—10 of Figure 1.

25 Referring now more specifically to the accompanying drawings, wherein like numerals indicate similar parts throughout the various views, 10 designates a bed plate of any suitable construction, and which may if desired be rigidly secured, as by bolts 12, to any suitable foundation indicated generally as 14, although it is to be understood that this base may be made portable in any suitable manner, when preferred.

30 As shown best in Figures 1 and 2, a framework comprising a pair of standards 16 are vertically disposed upon the base or bed plate 10, being suitably secured thereto as by welding or the like 18, these standards being disposed in parallel relation as shown in Figure 2, and being rigidly braced from the base plate 10 or by means of inclined straps 20 which if desired may be welded to the bed plate 10 and to the standards 16.

35 As shown best in Figure 3, the standards 16 at their upper extremities are each provided with a laterally extending terminal portion 22 to which is secured as by pivot pins 24, a pair of inwardly and angularly disposed arms 26 adapted to have pivoted or oscillatory motion upon the standards 16.

40 Attention is next invited to Figure 4, wherein it will be seen that the bed plate 10 is provided with a suitable depressed well or cupped shaped socket 28 while a tubular cylindrical casing 30 is disposed above the bed plate 10 in alignment with this socket and has its lower end annularly enlarged as at 32 for engagement with the bed plate.

A vertically disposed axle or shaft 34 having its lower end conically tapered as at 36 to conform generally to the tapering bore of the socket 28, is suitably journaled for rotation in the casing 30 and socket 28 by means of lower and upper anti-friction roller bearings indicated at 38 and 40. Suitably secured upon the upper end of the axle 34 is a ring gear 42 which as shown in Figure 5, is in mesh with a driving gear 44 driven by an electric motor or the like 46 suitably secured to the exterior of the casing 30 adjacent the upper end.

Rigidly secured to the upper extremity of the shaft or the axle 34, for rotation therewith, is a base plate 48, which may be of any suitable shape but is preferably circular or annular as shown in Figures 3, 4 and 5. The gearing 42 and 44 is disposed together with the driving motor 46 immediately below the under surface of this base plate in the interest of compactness and simplification of the rotating means of the device.

As shown more clearly in Figures 1 and 2, a pair of electro-magnetically operable vibrators, indicated generally at 50, and which are preferably of conventional and well-known design, are secured in a detachable manner to the upper portion of the casing 30, in a position adjacent to the motor 46, these vibrators having upwardly extending plungers 52 adapted during operation to impact upon and vibrate the base plate 48 and the mold detachably secured thereto, in a manner to be subsequently set forth.

Suitable electric cables or conductors 54 and 56 extend from the electro-magnetic vibrators 50 and the electric driving motor 46 respectively, and are respectively connected to foot operated switches or control means 58 and 60 which are connected to a suitable source of electric power as by cables 62. Preferably, the foot operated switches are disposed adjacent the base plate 48 in convenient position for ready manipulation by an operator of the device.

Electrical conducting means indicated at 64 extends from the foot operated switch or control 16 to the interior of the brake casing 32 of the housing 30, the arrangement preferably being such that the brake operating circuits to the cable 64 is alternatively applied in alteration with the operation of the electric motor 46 through the cable 56. In other words, the motor 46 and the electro-magnetic brake operating means are ultimately operable by an actuation of the double acting switch 60. The construction of this switch, and of the electro-magnetically operable brake may be of conventional design and form no part of this invention, Figure 6 indicating diagrammatically for explanatory purposes only a suitable type of electro-magnetically operable brake. As will be seen by reference to Figures 4 and 6, the axle 34 within the angular drum or housing 32, is provided with an angular enlargement 66 which may be provided with a suitable peripheral friction lining or the like, and which is encircled by a pair of contractible semi-circular brake shoes 68, having fixed pivots 70 at one end thereof and an electro-magnetic solenoid 72 connected to their opposite extremities. Obviously, upon energization of the solenoid 72, the brake shoes 68 may be selectively applied or released to the enlarged annular brake drum 66, thereby stopping the shaft 34 from rotation and securing the same in stationary positions. Obviously, suitable spring means, not shown, may be provided for automatically releasing, or applying the brake shoes as desired.

Alternatively, a hydraulic brake system may be employed instead of an electro-magnetic brake mechanism if desired. For this purpose, as shown in Figure 7, the enlarged brake drum 66 upon the axle 34 may be selectively engaged by the semi-circular brake shoes 68 pivoted as at 70, while the opposite end of these brake shoes may be connected as by a hydraulic pressure as by means of a conduit 76. Any suitable control means may be provided for actuating and controlling the application of and release of pressure to the hydraulic cylinder 74 in response to the above mentioned actuation of the foot control switch 60 in the manner above mentioned.

In accordance with the principles of this invention, a mold of any suitable type, and indicating as being of cylindrical shape, is shown at 78 in Figures 1, 2, 8, and 10. This mold preferably consists of a hollow, generally cylindrical casing formed in complementary vertically divided halves, detachably secured together as by flanges 80 and bolts 82. The interior of the mold may be of any suitable shape consistent with the purposes intended, and is illustrated as being of generally cylindrical contour with its lower extremity of tapering or narrowing diameter while its upper extremity is pointed in order to form a concrete article suitable for use as a practice bomb or projectile. The upper portion of the mold 78 is further provided with an upper open-ended neck portion 84 having a generally conical internal surface 86. This upper neck portion 84 and its internal surface 86 provide a means for receiving an improved construction of mold filling means, and further serves to journal or support the mold for rotation in a manner to be subsequently set forth.

As shown more clearly in Figures 1, 2, and 3, the upper surface of the annular, rotating base plate 48 is provided with a plurality of adjustable jaws or brackets 88, which are adjustable radially of the center of rotation of the base plate as by means of fastening bolts 90. As shown best in Figure 3, the brackets 88 are preferably L-shaped, with their upwardly extending legs being adapted to engage and embrace the outer circumference of the lower end of the mold 78, while the horizontally extending legs are longitudinally slotted as at 92 for sliding movement upon the adjusting bolts 90. By means of this construction, the clamps 88 may be adjusted to accommodate molds of various sizes and for readily centering the same upon the axis of rotation of the base plate 48.

Attention is now directed to Figures 1, 3, and 9 for a clearer understanding of the mold journaling and filling means. The angularly disposed arms 26 are connected with the outwardly extending handle 96, by means of a connecting portion consisting of a hollow annular ring 98. Thus, as shown in Figure 3, the handle 96 and arms 26 are generally arranged in Y-shaped formation with the hollow ring 98 being at the junction of the arms and legs of the Y. The ring 98 is provided with diametrically disposed transverse slots 100 within which are received for a limited lateral movement, a pair of laterally extending pins 102 secured at diametrically opposite points upon the outer circumference of the neck portion 104 depending from a filling funnel 106. The lower part of the neck portion 104 is conically tapered and has journaled upon its outer circumference as by means of roller bearings 108, a conical ring or collar 110 freely rotatable upon the neck portion of the funnel. The outer surface of the ring 110 is so contoured and shaped as to have a snug

and tight sliding fit within the above mentioned conical bore 86. By this means, when the handle 96 and arms 26 are lowered, the ring 110 is tightly disposed within the conical bore 86 of the neck portion 84 of the mold, said ring and neck portion of the mold being thus freely rotatable and journaled upon the relatively stationary outer bearing surface of the neck portion 104 of the funnel member. The throat or neck of the funnel is provided with an inwardly extending die member 112, whose lower surface is suitably contoured and concaved as at 114, to conform to the inner contour of the mold, and cooperate therewith in forming a pointed nose upon the article to be formed in the mold. Thus, when the mold is rotated, after the same has been suitably filled with cementitious or concrete material through the filling funnel 106, the stationary die 112, and its concave surface 114 will have relative rotary motion with regard to the mold, and thereby shapes the material in the mold to a pointed nose configuration as indicated by the dotted lines of Figures 1, 8 and 9.

A suitable hopper 116 having a discharge neck 118 and a discharge control means 120 is suitably mounted above mold 78 in a position to discharge its contents to the funnel portion 106 and thereby charge the interior of the mold.

From the foregoing, it is believed that the manner of operating the device will be now readily understood. A series of molds 78, of suitable shape and size, may be sequentially lifted by a crane (not shown) to the rotary base plate 48, clamped and centered thereon by means of the brackets 88, and the handle 96 then manipulated to position the filling funnel 106 within the neck of the mold in the position indicated in Figure 9. During this operation, indicated by the full line and dotted line showing in Figure 1, it will be seen that the handle 96 and legs 26 have an arcuate movement about the pivot pin 24. Since the collar 110 which is to be forced into tight sealing engagement with the bore 86 will necessarily have a relatively straight line movement, a relative displacement of the filling member upon the pivotal arms 26 will be necessary, this displacement being permitted by the pin and slot construction 100 and 102. When positioned in the manner shown in Figure 9, the filling funnel 106 and its neck 104 are supported in a stationary position upon the standards 16, while the collar 110, tightly fitted into the bore 86 of the neck 84 in the mold 78, is rotatably journaled upon the neck of the filling funnel by means of the anti-friction rollers 108. Thus, the mold 78 is rigidly attached to the base plate 48 at its lower end and is rotatably journaled upon a bearing member consisting of the collar 110 and the anti-friction rollers 108. A suitable charge of concrete or other material is now delivered from the hopper 116 by means of the control member 120 into the funnel portion 106, and thence passes into the interior of the mold 78. Obviously, as this material piles up or accumulates in the mold, it will tend to reach a shape indicated by the dotted lines 122 of Figure 8. However, either during the filling of the mold or after the mold has been substantially filled, the electro-magnetic apparatus 50 may be now actuated to jar and shake the mold and its contents and cause the material to thus assume a substantially level position within the mold. This vibratory movement of the support plate 48 and mold 78 is indicated by the exterior dotted line showing of Figure 8. After the mold has been suitably charged and filled, and the vibratory

treatment is completed to cause a uniform packing or density of the concrete within the mold, the electric motor is now operated to cause rotation of the mold, whereby the centrifugal force produced will cause any excess moisture within the concrete to be hurled against the inner circumference of the mold, thereby producing a smooth finish upon the concrete article within the mold.

It should be here noted that the automatic brake means will be continuously applied throughout the shaft 34 against rotation, as well as the mold 78 attached to the base plate 48, except when the motor 46 is energized to produce rotation. This facilitates charging of the mold and handling of the same in securing the mold to and removing it from the base plate, and is an important advantage of this invention.

After the mold has been charged and rotated, the die member 112 being held stationary will produce a smooth conical point upon the material within the mold during the rotation thereof. After this treatment is completed the filling funnel may be elevated, the clamps 88 loosened and the mold and its contents removed from the base plate 48 by a second crane or the like, not shown. The entire treatment of placing a mold upon the rotating plate, charging the same, agitating and rotating the contents and then removing the mold will require a relatively small period of time whereby a large number of molds may be handled and treated by this apparatus with a minimum of labor and with a considerable saving of time.

After the molds and their contents have been removed from the rotatable plate 48, they may be permitted to set or harden for a considerable length of time, and the molds then removed from the concrete article therein, and then renewed.

Since various modifications will readily occur to those skilled in the art after a study of the foregoing specification and accompanying drawings, it is not desired to limit the invention to the exact construction shown and described, but all suitable modifications may be resorted to and falling within the scope of the appended claims.

What I claim as my invention is:

1. A centrifugal concrete molding machine comprising a base, driving means for rotating said base, a mold having a neck at its upper end, means for detachably retaining and adjusting said mold upon said base radially of the center of rotation thereof, vibrator means for agitating said base, a support adjacent said base, a funnel, means for pivoting said funnel upon said support for removably positioning said funnel within said neck, a die in said funnel for molding the upper end of the concrete, and a member in said neck for axially journaling the upper end of said mold, said driving means including a vertical casing, a shaft rotatably journaled in said casing and supporting said base for rotation therewith, and a brake mechanism mounted upon said casing and operatively engageable with said shaft.

2. The combination of claim 1 wherein a driving motor is mounted on said casing and gearing interconnecting said motor and said shaft.

3. The combination of claim 1 wherein said vibrator means is mounted on said casing and operatively engages said base.

4. The combination of claim 3 wherein a driving motor is mounted on said casing and gearing interconnecting said motor and said shaft.

5. The combination of claim 1 wherein said

7
mold retaining means includes spaced adjusting nuts carried by said base, and substantially L-shaped brackets having vertical legs adapted to engage the outer circumference of said mold and horizontal legs including longitudinal slots for slidably engaging said nuts.

6. The combination of claim 1 wherein said member includes a collar and anti-friction rollers interposed between said collar and said funnel.

7. The combination of claim 6 wherein said mold retaining means includes spaced adjusting nuts carried by said base, and substantially L-shaped brackets having vertical legs adapted to engage the outer circumference of said mold and horizontal legs including longitudinal slots for slidably engaging said nuts.

8. The combination of claim 7 wherein said means for pivoting said funnel upon said support includes angularly disposed arms pivoted

5 at one of their extremities to said support, a ring secured to the other extremities of said arms, diametrically opposed transverse slots in said ring, and diametrically opposed laterally extending pins carried by said funnel and slidably received in said slots.

9. The combination of claim 8 and a handle carried by said ring.

HENRY A. WIESNER.
